Geo Kirk

ATTORNEY

UNITED STATES PATENT OFFICE.

HELENA A. LYON, OF TOLEDO, OHIO.

DESIGN FOR A DOLL.

60,869.

Specification for Design. Patented Apr. 18, 1922.

Application filed May 31, 1921. Serial No. 473,906. Term of patent 3½ years.

To all whom it may concern:

Be it known that I, HELENA A. LYON, a citizen of the United States of America, residing at Toledo, Lucas County, Ohio, have invented a new, original, and ornamental Design for Dolls, of which the following is a specification, reference being had to the accompanying drawing, forming part thereof.

Fig. 1 is a front view of a doll, showing my new design; and

Fig. 2 is a side view of said doll.

I claim:

The ornamental design for a doll as shown.

HELENA A. LYON.
